TELEPHONE SYSTEM

Application filed December 14, 1931. Serial No. 580,779.

The present invention relates to telephone systems in general, but is concerned more particularly with automatic telephone systems employing the well known Strowger vertical and rotary switching mechanism; and the main object is the production of new and improved circuit arrangements for enabling the sets of contacts in the bank of a selector to be variously apportioned amongst the trunk groups accessible from such selector.

GENERAL DESCRIPTION

As is well known, the ordinary Strowger switch has one hundred sets of bank contacts arranged in ten horizontal rows or levels. When this switch is used as a trunk selector, each level of contacts is ordinarily indexed by different digits and has a separate group of trunks connected thereto. The selector switches are ordinarily mounted side by side in groups or "shelves", with a permanent multiple between the contact banks of all the switches in a shelf, and with arrangements for multiplying the banks of a number of shelves together and for connecting the bank multiple with outgoing trunks; as is explained in the McElyea Patent No. 1,633,118, granted June 21, 1927. The number of shelves multiplied together as regards a given level depends upon the relative amount of traffic carried by the level in question.

In multi-office telephone systems, the various groups of trunks accessible to an office selector often vary greatly in size amongst themselves. Although, by using suitable grading, a trunk group can be formed which is in effect a unitary group, but contains many more trunks than there are contact sets allotted to the group in the bank of any one selector, it is desirable, nevertheless, from the standpoint of securing the greatest possible efficiency in each individual installation, to be able to increase and decrease the number of contact sets allotted to a contact group to an extent dictated by the relative size and cost-per-trunk of the trunk groups concerned. To this end, the circuit arrangement has been modified in order to enable the size of a contact group in the bank of the selector to be

expanded or contracted at will by including any desired portion of the contacts in the next higher level in the same trunk group with the contacts in any given level. With this novel arrangement, any level may be divided into two parts, each part being indexed by a separate digit and belonging to a different trunk group; one part is indexed by the digit normally assigned to the preceding, lower level, while the other part is indexed by the digit normally assigned to the level in question.

In operation, the improved selector responds to the digit dialled in the usual manner by raising its wipers opposite the desired level of bank contacts. If the digit dialled indexes a group lying partly in the corresponding level and partly in the next higher level, the operation ensuing at the end of the regular directed movement of the selector depends upon whether there is an idle trunk available in the selected level or not. If there is an idle trunk available, the wipers of the selector are automatically rotated in search of this idle trunk in the usual manner. But if there is no idle trunk in the selected level, the wipers of the selector are automatically stepped to the next higher level and are there rotated over the contacts in such level to test the contacts assigned to the digit dialled.

It will be understood, of course, that selectors which are operated to take an additional vertical step automatically responsive to an all-trunks-busy condition are not broadly new, such selectors being known as vertical hunting selectors. Whenever such selectors have been used in the past, however, the number of contacts in a selector bank assigned to a trunk group is always increased in multiples of ten, by assigning two levels to a trunk group instead of one, or by assigning additional levels as may be required or desired. When such selectors are used, it is manifest that the total number of trunk groups accessible to the selector is reduced by an amount depending directly upon the number of levels of contacts taken over for overflow work. With the improved selector herein disclosed, however, the number of trunk

groups accessible to a selector need not be reduced so long as no trunk group has more than nineteen contact sets allotted thereto, for the additional contacts allotted to one 5 trunk group are in effect merely taken from some other group (which other group is thereby reduced in size), and no group need be entirely cancelled.

From the foregoing explanation, it will be 10 seen that the improved selector about to be described in detail is arranged so that great flexibility is afforded in apportioning the available total number of contact sets amongst the trunk groups which must be reached from the selector.

15 A feature of the improved selector is that two separate test wipers are used, cooperating with separate bank contacts, and that one or the other of these test wipers is connected up during the automatic rotation of the selector, depending upon whether the selector is being rotated over a level to which it was raised directly responsive to the dialled impulses, or being rotated over a level to which 20 it was raised from a lower level by an automatic testing operation at the end of the directive operation. By the use of suitable circuits cooperating with the two test wipers, the selector is able to discriminate between the 25 trunk lines normally assigned to a given level and the trunk lines belonging to the group starting in the next lower level.

Description of drawing

30 Referring now to the drawing, comprising a single sheet, which shows by means of the unusual circuit diagrams a sufficient amount of apparatus in a telephone system embodying the features of the invention to enable the 35 invention to be understood. More in particular, the drawing shows the circuits of a selector constructed in accordance with the invention, which selector is accessible by way of the trunk line comprising conductors 11, 12, and 13 and is equipped with test wipers 31 and 32 and line wipers 33 and 34, which are arranged to move over the contacts in bank sections 35, 36, and 37, to which trunk lines such as T10 and T11 are connected.

40 The selector is provided with line relay 20, release relay 21, series relay 22, series auxiliary relay 23, discriminating relay 24, and switching relay 25. In addition, the selector is provided with the usual vertical, rotary, and release magnets 27, 28, and 26; and it has the off-normal spring contacts 16, 17, and 18, as well as the overflow contacts 14 and 15, which are operated only in case the wipers 45 31-34 are driven beyond the last set of bank contacts in a selected level. The dial-tone and busy-tone transformers 9 and 10 (common to the selector shown and other similar 50 selectors) are connected by leads 29 and 30 with the overflow contacts 14 for the usual and well understood purposes.

The selector, as illustrated, is of the so-called battery searching type in that it hunts for a trunk line having a battery connection thereon.

The dial tone source is associated with the 55 selector under the assumption that the selector is a first selector, to which the connection is extended automatically upon the removal of the receiver and in the well known manner. It will be understood, of course, that, if this 60 selector is used as a subsequent selector in the trunking system, the dial tone connection is replaced by a ground connection on the middle overflow contact spring of group 14.

The selector is also provided with a vertical 65 test wiper 38, which is arranged to make successive contact with the contacts in the vertically disposed row as the movement of the switch responsive to dialled impulses progresses.

The contact grouping

The grouping of the bank contacts will now be explained. 35, 36, and 37 indicate three 70 separate bank sections of the selector, sections 35 and 37 each comprising one hundred contact pairs arranged in the customary ten levels (of which only three are shown), while section 36 comprises one hundred contacts similarly arranged. Considering the bank 75 sections collectively, a contact set includes a pair of contacts of section 35, the corresponding contact of section 36, and the corresponding pair of section 37.

80 It is assumed that the trunk group to which the digit 1 is assigned is a group of rather expensive interoffice trunks, while the trunk groups to which the digits 2 and 3, respectively, are assigned are either small trunk groups or else are relatively inexpensive 85 groups not requiring the efficient trunk-use demanded by the first group. A total of 90 thirty contact sets, comprising the first three levels of the selector bank (all three of the 95 illustrated levels) have been assigned to the 100 three trunk groups above mentioned. As indicated by the following table, all contact sets in the first level, together with the first six contact sets in the second level have been assigned to group 1; the last four contact sets in the second level together with the first 105 three contact sets in the third level have been assigned to group 2; and the last seven contact sets in the third level have been assigned 110 to the third group:

Trunk groups	Contact set numbers	Number of contact sets
1-----	11 to 10, 21 to 26	16
2-----	27 to 30, 31 to 33	7
3-----	34 to 40	7
		30

125 In explanation of the information given in 130

the second column of the above table, it may be pointed out that contact set number 11 refers to the first contact set in the first level, and that the succeeding contact sets in the first row are designated 12, 13, 14, etc. to the ninth set, which is numbered 19, and the tenth set is numbered 10. The numbering of the contact sets in the higher levels follows the same plan.

It will be understood, of course, that the above indicated apportionment of contact sets amongst the three trunk groups is given by way of example only and that the relative sizes of the assigned contact sets may be varied at will. It will be understood, moreover, that the size of the third contact set may be increased, if desired, by assigning contact sets of the fourth level to the same trunk group, following the plan used in connection with the first and second trunk groups.

DETAILED DESCRIPTION

The invention having been described generally, a detailed description of the operation of the apparatus shown will now be given.

Seizure of the selector

It will now be assumed that the selector shown in the drawing is seized over the conductors 11 to 13, in which case a ground potential is applied to conductor 11, and the loop from a calling line is extended to talking conductors 12 and 13. The application of a ground potential to conductor 11 results merely in a momentary flow of current through the resistance element 19, and in the guarding of the selector against seizure from other sources.

The closing of the loop from the calling line to conductors 12 and 13 results in the operation of line relay 20 through the contacts of switching relay 25. When line relay 20 operates, it opens a point in the circuit of vertical magnet 27 at its lower armature, and at its upper armature it closes a circuit for the upper winding of release relay 21 in series with the lower windings of relays 22 and 21. More in detail, the circuit closed at the upper armature of relay 20 is as follows: from ground by way of the upper and lower off-normal springs 18, normally closed contacts controlled by the inner-upper armature of release relay 21, upper winding of relay 21, upper armature of relay 20, and the lower windings of relays 22 and 21 to battery. The current-flow through this circuit is sufficient to operate release relay 21, whose upper winding has a relatively large number of turns, but series relay 22 is not operated in this circuit because the lower winding of relay 22 has only a relatively small number of turns. The same is true as regards the lower winding of relay 21.

When relay 21 operates, it opens a point in the circuit of release magnet 26 at its lower

armature; places a ground potential on release trunk conductor 11 at armature 51 so as to maintain conductor 11 grounded after the ground potential has been removed at the point of seizure; supplies ground potential directly to the lower terminal of its upper winding at its inner-upper armature in substitution for the ground potential initially applied through off-normal contacts 18; and at armature 52 it applies ground potential by way of off-normal contacts 18 to the upper winding of series relay 22, thereby closing a circuit through the upper winding of relay 22 and the lower winding of relay 21, in which circuit the upper winding of relay 22 is shunted around the upper winding of relay 21 and the lower winding of relay 22. The closing of this new circuit does not disturb the already-operated relay 21, but it results in the strong magnetization of and the immediate operation of series relay 22, as the upper winding of relay 22 comprises a relatively large number of turns.

When relay 22 operates, it prepares a new circuit for its own upper winding at its upper armature; opens a point in the connection extending to vertical test wiper 38 at its lower armature; and at its inner-lower armature it closes a circuit for the resistance-shunted, series-auxiliary relay 23. Relay 23 thereupon operates and prepares an operating circuit for vertical magnet 27 at its inner-lower armature; prepares a test circuit by way of vertical test wiper 38 at its lower armature; and at its upper armature it opens a point in the circuit of rotary magnet 28.

From the foregoing explanation, it is seen that, responsive to the operation of line relay 20 when the selector is seized, relays 21, 22, and 23 operate successively, and that the selector is thereby prepared for operation in response to the usual manipulation of the calling device on the calling line.

Dial tone

Since the circuit of the upper winding of line relay 20 includes the secondary winding of the dial-tone transformer 9, dial-tone current is transmitted over conductors 12 and 13 to the calling substation, thereby giving a characteristic signal to the calling subscriber to inform him that he may now start to dial the desired number.

Directively setting the selector

When the first digit of the desired number is dialed, line relay 20 is deenergized momentarily a number of times depending upon the value of the dialled digit. Each time it is momentarily deenergized, line relay 20 closes a circuit for vertical magnet 27 at its lower armature, whereupon vertical magnet 27 is operated to raise the shaft of the switch, together with the wipers affixed thereto, one step. By the operation of vertical magnet 27

the wipers are, therefore, raised step by step until they come to rest opposite the desired level of bank contacts. As a further result of each momentary deenergization of line relay 20, the upper winding of relay 21 is placed in a local closed circuit at the normally closed contacts controlled by the upper armature of relay 20, and the initial circuit for the upper winding of relay 21 through the lower windings of relays 22 and 21 is opened. Since the lower winding of relay 21 has only a relatively small number of turns therein and cannot remain operated in series with the upper winding of relay 22, the relay is held operated between successive impulses by virtue of the circulating current flowing in the closed circuit including the upper winding of relay 21.

As a result of the mechanism of the selector being moved from its normal position, off-normal contacts 17 prepare a circuit for release magnet 26; off-normal contacts 16 disconnect resistance element 19 from conductor 11 and prepare a circuit for rotary magnet 28; and off normal contacts 18 open the initial circuit of the upper winding of series relay 22 in series with the lower winding of release relay 21, and close a new circuit for these two windings as follows: from ground by way of the inner-upper armature of relay 21, normally closed contacts controlled by the upper armature of relay 20, upper armature of relay 22, the normally open off-normal contacts in group 18, armature 52, upper winding of relay 22, and the lower winding of release relay 21 to battery. By this explanation, it will be seen that the circuit initially established through the upper winding of relay 22 and the lower winding of relay 21 has been shifted so that it is dependent upon normally open contacts controlled by relay 20, and is closed, therefore, only while relay 20 is in a deenergized condition.

Each time relay 20 re-operates following the delivery of an impulse to vertical magnet 27, it removes the shunt from around the winding of relay 21, whereupon this winding is again included in circuit series with the lower windings of relays 22 and 21. At the same time, with the altered circuit for the upper winding of relay 22 in series with the lower winding of relay 21, current from the upper winding of relay 21 divides and a part of it flows through the upper winding of relay 22 on its way to the lower winding of relay 21. With relay 20 in an operated condition, it will be observed that the lower winding of relay 22 is connected in shunt of the upper winding of the relay, and both windings are in series with the two windings of relay 21. Under this condition, the current-flow through the windings of relay 22 in series with the windings of relay 21 is insufficient to maintain relay 22 operated, but relay 22 remains operated during the receipt

of the remaining impulses by virtue of the circulating current flowing through its two windings in series, the upper winding acting as the driving coil, shunted by the low-resistance, low-turn lower winding. 70

When line relay 20 comes to rest in an energized condition at the ends of the series of impulses, the circulating current through the two windings of relay 22 in series shortly subsides, permitting relay 22 to restore. Upon 75 restoring, relay 22 disconnects its own upper winding at its upper armature, so as to prevent the relay from subsequently operating until the selector has been released and again seized; it connects up the vertical test wiper 38 at its lower armature; and at its inner-lower armature it opens the initial circuit of the shunted series auxiliary relay 23. Relay 23 remains operated for a slight interval because of the circulating induced current 80 which flows through its winding in series with the shunting resistance element. 85

The vertical test circuit

For the purpose of this description it will 90 be assumed that the digit received at the selector is the digit 1, in which case the wipers 31 to 34 and the wiper 38 have been raised one step and are now standing opposite the first level of bank contacts. 95

It is to be noted that the vertical test wiper 38 is now resting on a test contact associated with the first level of bank contacts. As will be pointed out subsequently, this contact is grounded in case all the trunk lines connected 100 to the contact sets in the first level are in use, in which case the wipers of the selector are automatically given an additional vertical step to bring them opposite the second level. 105

Trunk hunting

For the purpose of the present description, it will be assumed first that at least one of the trunk lines accessible from the first level of contacts is idle, in which case no ground potential is encountered by the vertical test wiper 38, and the automatic vertical step is not taken. Under this condition, the falling back of the series auxiliary relay 23, which follows closely upon the restoration of relay 22, results in the closure of a circuit for rotary magnet 28 to rotate the wipers over the first level of bank contacts. The circuit for rotary magnet 28 includes armature 51 of relay 21, off-normal contacts 16, overflow contacts 15, upper armature of relay 21, upper armature of relay 23, inner-lower armature of relay 25, and the self-interrupting contacts of magnet 28. 115 120 125

Trunk seizure

The automatic rotation of the wipers responsive to the buzzer-like action of magnet 28 continues until switching relay 25 operates, upon an idle trunk being encountered. 130

Assuming that the first idle trunk line encountered is the trunk T10, extending from the tenth set of bank contacts in the first level, the advance of the wipers continues until this trunk line is reached, whereupon the normally connected test wiper 32 encounters a battery potential by way of test conductor 34, completing an operating circuit for the upper winding of switching relay 25 to ground at armature 51. Upon operating, relay 25 opens the circuit of rotary magnet 28 at its inner-lower armature (thereby terminating the rotary movement), at the same time completing a locking circuit for its lower winding in series with rotary magnet 28. Rotary magnet 28 does not operate in series with the lower winding of relay 25 on account of the high resistance of this winding. Switching relay 25 also opens a point in the circuit of release magnet 26 at armature 53; connects the now-grounded incoming release-trunk conductor 11 directly with the test wiper 32 at its upper armature, thereby shunting its upper winding; and at its two lowermost armatures it disconnects the incoming conductors 12 and 13 from the windings of the line relay 20 and extends them by way of wipers 33 and 34 to conductors 35 and 36. Responsive to the above-mentioned operation of switching relay 25, the usual line and release relays (not shown) associated with the trunk T10 are operated, and ground potential is placed on conductor 34, thereby providing a holding circuit for the selector and for the preceding switching apparatus after the slow-acting release relay 21 of the selector illustrated has fallen back, as will now be explained:

When line relay 20 is disconnected at the contacts of relay 25, it falls back and closes a point in the circuit of vertical magnet 27 at its lower armature. Vertical magnet 27 is not operated at this time because the series auxiliary relay 23 is in a restored condition. Line relay 20, at its upper armature and associated contacts open-circuits and short-circuits the upper winding of the release relay 20, at the same time opening the circuit through the lower windings of relays 22 and 21 (relay 22 is in a restored condition at this time). It is to be noted that series relay 22 does not operate at this time because its upper winding has been disconnected at the upper armature of the relay. Relay 21 falls back as soon as the circulating current in the upper winding subsides somewhat.

Releasing

When the ground potential is removed from release trunk conductor 34 of trunk T10 when the connection is to be released, switching relay 25 restores and closes a circuit for release magnet 26 at armature 53. By the operation of release magnet 26 the selector is restored to normal position, whereupon the release-magnet circuit is opened at off-normal contacts 17, while at off-normal contacts 16 battery potential is re-applied to conductor 11 by way of resistance 19 so as to mark the selector as available for further use.

Selecting a trunk in the next higher level

It will now be assumed that all the trunk lines accessible from the first level of bank contacts are in use when the wipers of the selector are brought to rest opposite the first level of bank contacts as hereinbefore described. Under this condition, there is a selector in engagement with each of the trunk lines accessible from the first level of bank contacts. Keeping in mind that the contact sets and vertical test contacts are multiplied together throughout all of the selectors having access to the trunk lines under discussion, it will be seen that ground potential is extended by bridging wipers, such as wiper 31 of the selector illustrated, through the contact multiple to all of the number one contacts in the bank of the vertical test wipers, such as test wiper 38. Under this condition, therefore, test wiper 38 encounters a ground potential, resulting in a circuit being closed for vertical magnet 27 through contacts of the restored series relay 22 and contacts of the still-operated slow-restoring relay 23. This circuit includes the lower winding of discriminating relay 24 and the self-interrupting contacts of magnet 27. Relay 24 and vertical magnet 27 energize in series, relay 24 operating slightly ahead of the magnet, which has a larger, heavier armature, and must elevate the shaft. When relay 24 operates, it prepares a locking circuit for its upper winding at its inner armature, and at its upper armature it disconnects test wiper 32 and connects up test wiper 31.

When magnet 27 near the end of its stroke, and just before vertical test wiper 38 leaves the first-level test contact and comes into engagement with the associated second-level contact, it interrupts its own circuit and the circuit of relay 24, whereupon vertical magnet 27 deenergizes, and again closes its interrupter contacts. The vertical magnet can not again operate, however, because the series auxiliary relay 23 has a sufficiently stiff adjustment that it falls back and disconnects vertical test wiper 38 before magnet 27 can operate the second time, even though the second-level test contact may be grounded. It may be pointed out that discriminating relay 24 is rendered sufficiently slow-acting by the usual copper collar around its core that it does not fall back while the self-interrupting contacts of the vertical magnet are open. As soon as relay 23 falls back and vertical magnet 27 has restored its interrupter contacts, a locking circuit exists for relay 24.

in series with vertical magnet 27, and by way of both windings of relay 24 in series. Magnet 27 does not operate in this circuit because of the relatively high resistance of the 5 upper winding of the relay.

By the above-described automatic vertical stepping operation the wipers of the selector have been raised one step from their set position opposite the first level to a position opposite the second level of bank contacts. The regular rotary movement is now brought about by the rotary magnet 28 and responsive to the closure of the circuit of rotary magnet 28 at the upper armature of the series-10 auxiliary relay 23. Since the discriminating relay 24 is now operated, and the test winding of relay 25 has been disconnected from wiper 32 and transferred to wiper 31, the testing is performed in the second level of bank section 35 in place of in the second level of bank section 36, as is done when the wipers are brought opposite the second level of the bank contacts responsive to the dialling of the digit 2. Assuming that the first set-15 of contacts in the second level is idle (the eleventh contact set in trunk group one), wiper 31 encounters a battery potential on conductor 37 of the trunk T11, whereupon switching relay 25 operates with the hereinbefore described results.

It may be particularly pointed out at this time that the release trunk conductors of trunk lines reached from the level above the one corresponding to the digit assigned to the concerned trunk group are connected to the bank section 35 instead of bank section 36, thereby enabling a discriminating test to be made so that there is no danger of the selector seizing a trunk line in other than 40 the dialled group.

All-trunks-busy condition

Assuming now that all trunks are busy in the first group when the digit 1 is dialled 45 as hereinbefore described, the wipers are given an automatic vertical step following their alignment opposite the first level of bank contacts responsive to the digit 1. Following this additional and automatic vertical step, the wipers are rotated over the bank contacts in the second level in search of an idle trunk. Since the remaining six trunks in group one are all in use, the hunting action of the selector continues until the wipers pass 50 over all of the contacts in the second level, as no battery potential is encountered by wiper 31 on any of its contacts.

When the wipers 31 to 34 pass off the last set of bank contacts in the second level, the 60 overflow spring-combination, including contact sets 14 and 15, are actuated. At off-normal contacts 15 the circuit of rotary magnet 28 is interrupted, thereby terminating the rotary movement, while at the overflow contacts 14 busy-tone current is substituted for

dial-tone current, giving the calling subscriber a characteristic busy signal to prompt him to release the partially established connection and make the attempt later.

Completing a connection in the second group 70

Assuming now that the selector shown in the drawing is seized and prepared for operation in the usual manner and that the calling subscriber dials the digit 2, the wipers of the selector are stepped vertically into association with the second level of bank contacts, following which the series relay 22 falls back and connects up the vertical test wiper 38 in order to determine whether or not there is an idle trunk line available in the second level and assigned to group 2. Assuming that there is such a trunk line, vertical magnet 27 is not operated further, as no ground potential is encountered by wiper 38; and the hunting operation takes place on the second level. Since discriminating relay 24 is not operated in this case, the testing operation is performed with wiper 32. Since the first six contacts in the second level of the bank of wiper 32 are not connected to any trunk lines, the effective testing does not begin until the seventh contact set is reached. Either the seventh contact set or one of the succeeding contact sets is found to the idle, and the connection is completed in the usual manner.

From the explanation hereinbefore given, it will be understood that the wipers of the selector are automatically raised to the third level, and wiper 32 is replaced by wiper 31 in case all of the second-group trunk lines terminating in the second level are busy.

It will be understood, of course, that the manner disclosed herein for controlling the application of ground potential to the contacts in the vertical test bank is merely exemplary, and that suitable arrangements, including so-called chain relays connected to the release trunk conductors of the trunk lines involved may be used whenever found to be desirable.

What is claimed is:

1. In a two-motion selector switch having its bank contacts divided into parallel rows and having a motion in one direction to select a contact row and a motion in another direction to select a set of contacts in a selected row, means for assigning all of said contact sets to groups of trunk lines, said trunk line groups being equal in number to the rows of contacts, and means effective when the assignment is made so that the number of contact sets assigned to the several groups are unequal for causing the selector to respond to the designation of a trunk line group by hunting for and extending connection to any idle contact set assigned to such group. 115
2. In combination, a selector having its contact bank arranged in parallel rows, there 120

2. In combination, a selector having its contact bank arranged in parallel rows, there 130

being a separate digit assigned to each row, groups of trunk lines corresponding to said rows, respectively, one of said trunk line groups occupying contacts in the row assigned thereto and additional contacts in the next adjacent contact row, means in said selector responsive to a digit control for bringing the selector into association with the corresponding contact row, means for then causing the selector to search over the contact row for an idle trunk line, means effective in case all trunk lines reached from such contact row are in use and in case there are additional trunk lines in the same group reached from the next adjacent contact row for automatically advancing the selector to the next contact row before the trunk searching operation takes place, and means for restricting the trunk searching action of the selector to the trunk lines in the group corresponding to the digit in accordance with which the selector was initially positioned.

3. In combination, a selector having bank contact sets arranged in groups, each group normally corresponding to a separate digit designation, the contacts in one of said groups being divided between two trunk groups bearing different digit designations, means for bringing said selector into association with said contact group as a result of control being exercised over the selector in accordance with either of said two digit designations, means thereupon effective for starting said selector searching over the contact sets in said groups successively, and means automatically effective and dependent upon the digit in accordance with which the selector received its control for preventing the selector from making connection with any trunk line of one group and for permitting the selector to make connection with any idle trunk line in the other group.

4. In combination, a selector having its contact bank arranged in groups, means effective for setting the selector into association with a contact group by a directed movement or by a non-directed automatic movement, the contacts of said group being divided between two separate groups of trunk lines, and means effective depending upon in which of the two ways the selector was brought into association with the contact group for predetermining with which trunk group connection will be made.

5. In combination, an automatic trunk selector having its bank contacts arranged in groups, trunk lines connected in the bank of said selector and having different digit designations, means for operating said selector in accordance with the digit designation of any trunk line group to bring the selector into association with a group of contacts to which trunk lines of said group are connected, said selector having two test wipers, one being normally effective and the other being nor-

mally ineffective, means effective when said selector is brought into association with a group of contacts and responsive to all trunk lines terminating in the said contact group corresponding into the digit setting of the selector being in use for automatically operating said selector into association with a different one of the contact groups, and means thereupon effective for substituting the normally ineffective test wiper for the normally effective one.

6. In combination, an automatic trunk hunting selector switch having its contact bank arranged in groups, means for directly associating the wipers of said selector with said group in accordance with digit designations, means in said selector for causing the wipers to be brought into association with a contact group by means of a non-directed movement, said selector having two test wipers, and means for selecting either of said test wipers for use to the exclusion of the other, depending upon whether the selector is brought into association with a contact group by means of a directed movement or a non-directed movement.

7. In combination, an automatic trunking selector having its contact bank divided into groups, directing means for setting the wipers of said selector into association with any group by advancing the wipers successively from group to group, there being one trunk group occupying contacts in one contact group and certain of the contacts in the next succeeding contact group, with a second trunk group occupying the remaining contacts in the last-mentioned contact group, means effective when the selector is directly set on the first of said two contact groups for automatically giving the selector an additional non-directed movement to the next succeeding contact group in case all of the trunk lines connected to the contacts of the first contact group are in use, means thereupon effective for causing the selector to search for and seize any idle trunk line of the first group connected with the contacts of the second contact group, and means for preventing the selector from connecting with any one of the trunk lines of the second contact group unless the selector was initially and directly positioned on the second contact group.

In witness whereof, I hereunto subscribe my name this 11th day of December, 1931.

JOHN WICKS.
